UNITED STATES PATENT OFFICE

2,247,362

DRAFTING DEVICE

Howard A. Dibble, Jr., Hartford, Conn.

Application September 15, 1939, Serial No. 295,121

3 Claims. (CL. 33—104)

My invention relates to drafting devices. It has among its objects to provide an improved drafting device, and one especially adapted to use in drawing screws or screw threads, whereby the work of the draftsman is facilitated and expedited. A further object of my invention is to provide an improved drawing implement adapted to be used in connection with a T-square and of an improved construction adapted to engage a T-square in such manner that the device may be used in different relations with the T-square in such manner as to adapt it very conveniently to use on a wide range of work. A further object of my invention is to provide an improved drafting guide wherein, while obtaining the above advantages, it is made possible to produce a device which not only is adapted to provide a draftsman with a guide for any angle usually required in his work, but which further is adapted to be readily disposed in any desired relation with a T-square, while also being of such construction that complete accuracy is obtainable over long periods of use irrespective of wear. These and other objects and advantages of my construction will, however, hereinafter more fully appear.

In the accompanying drawing, I have shown for purposes of illustration, one embodiment which my invention may assume in practice.

In the drawing,

Figure 1 is a perspective view showing my improved device in outline and in use on a drawing board;

Fig. 2 is an enlarged detail top plan view of the device illustrated, and

Fig. 3 is an end elevation thereof.

In this illustrative construction, I have shown my improved guide member, generally indicated at 1, in use on a drawing board 2 and in connection with a T-square 3 thereon, the device 1 being shown in Figure 1 in a position exposing a drawing 4 on a sheet 5 attached to the board 2; this device 1 being of an improved construction as hereinafter described.

My improved guide member 1 is generally rectangular in form and herein in the form of a square provided at each corner with a right angled corner including elongated surfaces 6 of substantial length and extending away from the corner. Herein, these surfaces 6 on each side of the device 1 are indented by angularly disposed cut-out portions, generally indicated at 7, 8, 9 and 10. Of these, the cut-out portion 7 has straight sides or edges 11 disposed at an angle of 90° to each other in such manner that each

edge 11 is at an angle of 45° to the vertical and a 90° angle is included therebetween. The cut-out portion 8 herein includes edges 12 each disposed at an angle of 60° to the vertical and in such manner as to include an angle of 120° therebetween. The cut-out portion 9 also has its edges 13 disposed at an angle of 30° to the vertical in such manner as to include an angle of 60° therebetween, while the cut-out portion 10 has its edges 14 at an angle of 15° to the vertical in such manner as to include an angle of 30° therebetween. Further, it will be noted that these cut-out portions 7, 8, 9 and 10 are each disposed centrally of the side of the member 1 in which the cut-out portion is disposed, with all their vertices passing through a single central point which is the center of the device 1. It will further be noted that each edge of each cut-out portion is suitably marked, one edge bearing a legend indicating the number of degrees of inclination from the vertical, while a suitable legend indicating the number of degrees included is disposed along the other edge. Also, it will be understood that, if desired, a graduated or rule portion 15 may be provided along the several edges 6, i. e. around the portions of the periphery of the member 1 formed by these edges 6, and also on the various edges 11, 12, 13, 14, or on any selected edges of either set of edges, although to facilitate illustration I have herein only shown such graduations along the edges 6 and 14, i. e. adjacent the cut-out portion 10. Attention is also directed to the fact that my improved construction having the four corners makes it possible to provide, if desired, a series of circular openings 16 of different graduated diameter extending across the same between diagonal corners in such manner as to be readily useable, while it also makes it possible to use a like series of hexagonal openings 17 of different sizes, likewise disposed between diagonally opposite corners and herein transversely with respect to the series of circular openings 16.

As a result of my improved construction, it is made possible to cause any set of spaced edges 6 along any side of the member 1 to engage with the T-square, at the same time that complete accuracy of positioning of the member 1 relative to the T-square is assured. Further, it will be observed that the elongated edges 6 are long wearing, there being no points to wear down in service. Moreover, the member 1 is of such conformation and size that it may be readily spun about in the fingers by the draftsman in order to present the edges of any desired cut-out por-

tion to the work being done. Further, the cut-out portions 7, 8, 9 and 10 are symmetrical so that with the T-square remaining stationary the device 1 may be disposed with any side edge thereof in contact with the T-square without displacing the center line of the device. Similarly, in isometric work, the device may be turned to present any selected angle thereon without requiring re-centering of the device by movement of the T-square, the line intercepting the vertices of the angles on the vertically disposed edges always being equidistant from the T-square. Thus, when a different angle is required, the draftsman by a simple movement of the member 1 can readily bring the desired edges 11, 12, 13 or 14 into the proper relation to the work. Similarly, the various circular openings 16, or hexagonal openings 17, may be readily utilized in widely different positions by merely sliding the member 1 in reverse directions along the T-square. While the size of the device 1 may be varied, in ordinary practice, the same need be only approximately five inches square and be made of "Celluloid" or suitable material, in such manner as to enable the complete device to be readily and inexpensively produced. These and other advantages of my improvements will, however, be apparent to those skilled in the art.

While I have in this application specifically described one embodiment which my invention may assume in practice, it will be understood that the same is shown for purposes of illustration, and that the invention may be modified and embodied in various other forms without departing from its spirit or the scope of the appended claims.

What I claim as new and desire to secure by Letters Patent is:

1. A drafting device having a generally rectangular body including four protruding corner

portions the sides of which if projected would form a rectangle and also having an angular indentation in each edge between and defining said corner portions, each of said indentations having oppositely inclined edges forming a different included angle and each angle having the oppositely inclined edges thereof of equal length.

2. A drafting device having a generally rectangular body including four protruding corner portions the sides of which if projected would form a rectangle and also having an angular indentation in each side edge between and defining said corner portions, each of said indentations having oppositely inclined edges forming a different included angle and each angle having the oppositely inclined edges thereof of equal length, said indentations being symmetrically disposed in the side edges of said body with the apexes of all indentations disposed in lines passing at right angles through a common point at the center of said body.

3. A drafting device having a generally rectangular body including four protruding corner portions the sides of which if projected would form a rectangle and also having an angular indentation in each side edge between and defining said corner portions, each of said indentations having oppositely inclined edges forming a different included angle and each angle having the oppositely inclined edges thereof of equal length, and a plurality of relatively transversely disposed series of openings providing aids in drafting and each aligned in said body between diagonally opposite corners, one of said series comprising hexagonal openings having opposite flat sides thereof arranged parallel to opposite parallel side edges of said body.
